GARMENT HANGER SUPPORT AND CARD HOLDER

Samuel J. Cutaia, Houston, Tex.

Application February 17, 1947, Serial No. 729,108

3 Claims. (Cl. 40—10)

1

The present invention relates to a supporting device for use in such establishments as cleaning and pressing shops, the purpose of the invention being to provide for the hanging of suits, or other articles of apparel on conventional racks or supporting bars, in such manner that the garment of a particular customer can be readily found when called for. In connection with the above, the invention will be found to be of great assistance in storing the garments in the manner mentioned, in alphabetical, numbered, or other order, so that the possibility of any garment becoming lost or misplaced, even temporarily, is avoided.

Another object of the invention is to provide a garment support of the type mentioned, which permits suspending the garments on a conventional coat hanger or other support, in such manner as to insure that the garments are retained in a neat and pressed condition.

It will be apparent from the description of the invention herein, that the supporting device described will be of pronounced usefulness in establishments handling a great volume of business, and where it is necessary to space the overhead supporting bars relatively closely to one another. The invention provides for retaining the garments and their support so that identifying indicia on the support is constantly presented to the most convenient direction for recognition by attendants passing between the rows of garments.

Various other objects and advantages of the invention will be apparent as the description progresses. In the drawings:

Figure 1 is a top plan view of the support in use, while supporting garments from an overhead bar or rail, the view being presented as from a point above the rail, looking downwardly.

Figure 2 is a side elevational view of the assembled garments supported by the device from the rail, looking inwardly at an angle toward the rail from a point indicated by the arrow A in Figure 1.

Figure 3 is a side elevational view of the front face of the device itself.

Figure 4 is a top plan view of the device as positioned in Figure 3.

Figure 5 is another side elevational view of the device, showing its relation to the overhead rail, this view varying from that of Figure 3 in that the device has been turned through an angle of substantially 45°, in a counter-clockwise direction as viewed from the top.

Figure 6 is a top plan view of the device as presented in Figure 5, also showing diagrammatically the relation of the overhead rail.

2

Figure 7 is a side elevational edge view of the device, partially broken away, the view showing a portion of the device as it would appear when turned through substantially 90° from the position of Figure 3, in a clockwise direction, as viewed from the top.

Figure 8 is a horizontal sectional view through the supporting device taken along the line 8—8 of Figure 3.

Referring to Figures 3, 5 and 7, the device consists of a flat name plate portion 10 of metal, of generally rectangular form, the top, side, and bottom edges of this rectangular portion being appropriately cut as shown, and bent downwardly or inwardly to form respective card retaining flanges 12, 16 and 18. As indicated in Figures 7 and 8, these downwardly bent edges are spaced from the main body of the plate 10 in such manner as to provide slots 20 into which the upper, side or lower edges of the customer's identification card may be inserted and retained. The vertical side 22 of the plate 10 opposite the edge 16 does not have a channel as described, and it is from this side that the identification card is inserted into the holder. As described, the presence of a sharp edge may be avoided by bending the edge 22 rearwardly and flattening it against the rear surface of the plate, as shown at 24 in Figure 8. Connected centrally to the rear face of the plate 10, in any suitable way, such as by welding, and vertically disposed with respect to the length of the plate, is a garment supporting rod 26. This rod extends beyond both the upper and lower ends of the identification plate, and at its upper end it takes the form of a hook 28 for engaging the overhead rail, and the lower end is formed in a suitable manner as at 30, in order to provide for the removable attachment of the hook of a conventional coat hanger or the like, as shown in Figure 2. While the design of the lower end of the rod may vary, I have shown it as a closed loop, and more specifically in the form of a closed triangular loop which results from appropriately bending the end of the rod to form the triangle mentioned, the extreme end of the rod being secured as by welding to the initially bent portion thereof at the apex of the triangle mentioned, as at 32 in Figures 3 and 5.

The general manner of use of the device will be apparent from Figure 2. In this figure, the overhead rail is shown at R, and hanging from this rail are a series of the supporting devices, same being removably engaged on the rail by their hooks 28. The conventional coat hangers, indicated at C, are removably hung through the loop.

30, so that each garment is carried by its particular device. A sheet of paper, or card board, or the like, bearing whatever indicia is found necessary with respect to the particular garment is inserted from the edge 22 into and on the front face of the plate 10, being retained by the top, bottom and side guiding edges 12, 18 and 16 respectively. When an attendant searches for a customer's garment, he passes between the various rows thereof, suspended from parallel rails R, and selects the garment from the writing on the inserted cards, as will be apparent from Figure 2.

As has been mentioned, the supporting device is designed for most convenient presentation of information on the customer's card while at the same time providing for supporting the garments in orderly and space-saving relation in the usual manner, i. e., in planes at right angles to the length of the overhead supporting bar. In order to accomplish this, and referring to a comparison of Figures 3 and 5, the hook portion 28 is formed so that it lies in a plane substantially at 45°, when viewed from above, from the plane of the plate 10. Stated another way, the plane of the hook portion is bent 45° from the plane of the plate 10 in a counter-clockwise direction, as viewed from the top of the device, this being apparent from an inspection of Figure 4.

In addition to the above provision, the loop 30 is also formed in a plane displaced substantially 45° from the plane of the plate 10, but the displacement of the plane of the loop 30 is in the opposite direction from that of the hook portion 28, i. e., it may be said to be bent to an angle of 45° in a clockwise direction from that of the plate 10 as viewed from above. With this relationship, it will be apparent from Figures 4 and 6, that the plane of the hook portion 28 is at right angles to the plane of the loop portion 30. The result of these relative arrangements of the parts mentioned is that when the device is supported from an overhead rail R, the hook portion 28 will be at right angles to the rail R, which is the position most desirable for stability in hanging the device on the rail, and the loop portion 30 will lie in a plane beneath and parallel with the axis of the rail R, which is the position most convenient for suspending the hook of a coat hanger C on the loop 30 and at right angles to the rod or rail R. In this connection, the plate 10 is so designed, as to width, that when suspended from the rail, the dimension of the plate along the length of the rail is substantially equal to that necessary to accommodate an ordinary garment such as a man's suit, carried on the coat hangers C.

As will be evident from Figure 6, when an attendant passes between rows of garments, and moving along in the direction of the axis of the rod R, the front face of the plate 10 will be presented to him at an angle of substantially 45° from the vertical plane through the axis of the rod R, and due to the design and relation of parts as described, the customer's card will be presented to the attendant in a most convenient position for quick inspection. It will further be evident that by the arrangement described, when the garments are hung in close order on the overhead rail R there will be a minimum obscuring of one card by the plate which supports the preceding card, with respect to the direction of movement of the attendant between the rows of garments which are in stock.

The convenient relationship of adjacent supporting devices, and their customer's cards, will

also be evident from a comparison of Figures 1 and 2. It will be observed from Figure 1 that an attendant standing or moving through point A will be able to look directly against the front face of the supporting device, and as portrayed in Figure 2 there will be no substantial overlapping of the plates 10 of the supporting devices, as far as the view of the attendant is concerned.

The advantages as mentioned above will obviously be present, even though the articles of clothing are closely racked on the rods R, in order to take maximum advantage of the available space.

While the invention may be usefully employed in various establishments where clothing and the like is handled, it will be found to be of most pronounced usefulness in such as cleaning and pressing establishments. In these establishments, when a garment is received at the checking-in point, a list is prepared for each customer on a printed form, which contains a description of all garments as delivered by a particular customer. A distinguishing number or letter is placed on this list, and a corresponding mark is inscribed on the particular garments. The list is filed and the garments are sent to the work room for processing, and upon return from the work room, it is necessary to assemble the garments delivered by the individual customer and attach the proper list to the assembled garments. Obviously, a great deal of checking is required to locate each list and collect the proper garments to be grouped with that list.

In the use of the present invention, a special hanger is used for each customer, and a customer's list is made at the receiving office in the usual manner and the garments are sent to the work room. This list is then inserted in the holder or plate 10 of a particular supporting device, and this device is then suspended on the overhead rods in alphabetical or numerical order, arranged so that the list is presented for convenient reading, from the aisle. As finished garments are returned from the work room, each garment can be taken as soon as returned, and by its identifying mark, it may be suspended on a hanger or the like from the end of the loop 30 on the proper supporting device. The above system eliminates duplicate handling of the finished clothes, and avoids extended searches through great numbers of garments in order to assemble the garments of a particular order, prior to hanging them in the storage area awaiting call from the customer.

I claim:

55. 1. A garment support comprising a rigid rod adapted to assume a normally vertical position, said rod having an upper end bent into an open hook to removably engage over an overhead pipe rail or the like when said hook is in a vertical plane normal to the axis of said pipe or rail, said rod having a lower end bent to form a loop positioned directly below said hook for supporting conventional coat hangers or the like, said loop being formed to lie in a vertical plane at right angles to the plane of said hook, and a flat plate having means for receiving a customer's identification sheet or card rigidly secured to said rod between said hook and said loop and lying in a vertical plane between the planes of said hook and said loop.

60. 2. A garment support comprising a rigid rod adapted to assume a normally vertical position, said rod having an upper end bent into an open hook to removably engage over an overhead pipe rail or the like when said hook is in a vertical

75

plane normal to the axis of said pipe or rail, said rod having a lower end bent to form a loop positioned directly below said hook for supporting articles, and a flat plate having means for receiving an identification card or sheet rigidly secured to said rod between said hook and said loop and lying in a vertical plane displaced substantially 45° from the plane of said hook.

3. A garment support comprising a rigid rod adapted to assume a vertical position, said rod having an upper end provided with means for suspending said support, said rod having a lower end bent to form a loop positioned directly below said suspending means and which lies in a vertical plane, and a flat plate secured to said rod above said loop, said plate having a channel to receive a customer's identification card or sheet, said plate lying in a vertical plane which is dis-

placed from the plane of said loop by substantially 45°.
